(57) CLAIM

The ornamental design for a vehicle foot peg, as shown and described.

DESCRIPTION

FIG. 1 is a perspective view of the vehicle foot peg showing my new design, with the peg in a closed orientation;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof;

FIG. 8 is a perspective view of the vehicle foot peg, with the peg in an extended orientation;

FIG. 9 is a front elevational view of the vehicle foot peg of FIG. 8;

FIG. 10 is a top plan view of the vehicle foot peg of FIG. 8;

FIG. 11 is a bottom plan view of the vehicle foot peg of FIG. 8;

FIG. 12 is a right side elevational view of the vehicle foot peg of FIG. 8;

FIG. 13 is a left side elevational view of the vehicle foot peg of FIG. 8; and,

FIG. 14 is a rear elevational view of the vehicle foot peg of FIG. 8.

Broken lines shown are shown to illustrate unclaimed elements and form no part of the claimed design.
